UNITED STATES PATENT OFFICE.

NEWTON HOLLINGSHED, OF SEATTLE, WASHINGTON.

SWITCH.

1,269,444.

Specification of Letters Patent. Patented June 11, 1918.

Application filed October 20, 1917. Serial No. 197,684.

To all whom it may concern:

Be it known that I, NEWTON HOLLINGSHED, a citizen of the United States, residing at Seattle, in the county of King and State of Washington, have invented certain new and useful Improvements in Switches; and I do hereby declare the following to be a full, clear, and exact description of the invention, such as will enable others skilled in the art to 10 which it appertains to make and use the same.

This invention relates to improvements in railway switches and has for one of its objects the provision of a pair of switch points 15 adapted to be alternately moved to engage a frog so that a car can be switched from one track to another.

Another object of this invention is to provide a novel means for moving the switch 20 points into and out of engagement with the frog.

Another object of this invention is the provision of a railway switch of the above stated character which shall be simple, durable and 25 efficient and which may be manufactured and sold at a comparatively low cost.

With these and other objects in view as 30 will become more apparent as the description proceeds, the invention consists in certain novel features of construction, combination and arrangement of parts as will be hereinafter more fully described and claimed.

For a complete understanding of my invention, reference is to be had to the following 35 description and accompanying drawings, in which:—

Figure 1 is a plan view partly in section of a railway switch constructed in accordance with my invention,

40 Fig. 2 is a side elevation of the same,

Fig. 3 is a transverse sectional view taken on the line 3—3 of Fig. 1, illustrating the means of connecting the switch points together, and

45 Fig. 4 is a transverse sectional view taken on the line 4—4 of Fig. 1.

Referring in detail to the drawings, the numeral 1 indicates a supporting plate mounted upon railroad ties 2 and secured 50 thereto by fasteners 3. The supporting plate 1 supports one end of a frog 4 which has the usual branch rails 5 forming a portion of a switch.

A pair of converging switch rails 6 and 7

are pivoted to one of the ties 2 as illustrated at 8 and have their free ends disposed over the supporting plate 1 in close proximity to the frog 4. The free ends of the switch rails 6 and 7 have their opposing faces beveled as illustrated at 9 for the purpose of conforming to frog 4 when moved into engagement therewith. The switch rails 6 and 7 are connected so that they will be compelled to move in union by means of links 10 that are pivoted to ears 11 formed 65 upon the switch rails so that when one switch rail is moved into engagement with the frog 4, the free end of the other switch rail will be spaced therefrom so that a car or train may freely pass on to the switch rail that is 70 in engagement with the frog without engaging or interfering with the other switch rail.

The switch rails 6 and 7 have slidably mounted upon their outer faces elongated plates 12 on which are formed quadrant 75 switch point operating blocks 13 having their curved faces disposed outwardly from the switch rails into engagement with a series of converging guides 14 secured to the ties 2, whereby sliding the plates 12 upon the switch rails 6 and 7 in opposite directions, the blocks 13 will force one of the switch rails into engagement with the frog 4 and disengage the other switch rail 80 therefrom.

A rod 15 is pivoted to one of the blocks 13 upon the switch rail 6 and is in turn pivoted to a lever 16 that is pivoted upon one of the ties 2. A transverse operating rod 17 is journaled to one of the ties by 90 means of brackets 18 and has formed adjacent one end a crank 19 on which is journaled a rod 20 that is in turn pivoted to the other end of the lever 16.

One end of the operating rod 17 has its 95 end disposed at right angles to form an actuating arm 21 to which is pivoted the rod 22. The rod 22 is pivoted to one of the blocks 13 upon the switch rail 7, whereby upon rotating the operating shaft 17, one 100 series of the blocks 13 will be moved in one direction while the other series is moved in the opposite direction so as to cause the switch rails 6 and 7 to alternately engage the frog 4. The free end of the operating rod 17 may be connected in the usual manner to a switch target so that upon rotating the ordinary target the switch rails 6 and 105

7 will be caused to engage and disengage the frog 4 for the purpose of switching a car or train from one track to another.

While I have shown and described the 5 preferred embodiment of my invention, it will be understood that minor changes in construction, combination and arrangement of parts may be made without departing from the spirit and scope of the invention 10 as claimed.

What is claimed is:—

1. A railway switch comprising ties, a frog carried by said ties, switch points pivoted to said ties and located in close 15 proximity to the frog, plates slidable on said switch points, quadrant switch point operating blocks carried by said plates, guides carried by the ties and engaging the curved faces of the blocks, and an operating 20 means connected to the blocks and adapted to slide the plates in opposite directions

upon the switch points to cause said blocks to alternately move the switch points into and out of engagement with the frog.

2. A railway switch comprising a frog, 25 switch points pivotally mounted and disposed upon each side of the frog, links pivotally connecting the switch points, plates slidable on the side faces of the switch points, quadrant blocks having their straight 30 faces formed on the plates, guides engaging the curved faces of said blocks and means sliding the plates in opposite directions to cause the blocks to move the switch points by their curved faces engaging the guides. 35

In testimony whereof I affix my signature in presence of two witnesses.

NEWTON HOLLINGSHED.

Witnesses:

BLANCHE H. DIXON,
PAUL ZIMMERMANN.
